US00D493435S1

(12) **United States Design Patent** (10) Patent No.: **US D493,435 S**
(45) Date of Patent: **** Jul. 27, 2004**

(54) **TWO-WAY RADIO**

(75) Inventors: **Hartmut Heinrich Esslinger**, Sunnyvale, CA (US); **Howard Geoffrey Nuk**, Sunnyvale, CA (US); **Kevin Christian Coullahan**, Sunnyvale, CA (US); **Lucas Graeme Williams**, Sunnyvale, CA (US); **Peter Kossev**, Sunnyvale, CA (US); **Jon Christopher Lake**, Sunnyvale, CA (US); **William H. Robertson, Jr.**, Lauderdale, FL (US)

(73) Assignee: **Disney Enterprises, Inc.**, Burbank, CA (US)

(**) Term: **14 Years**

(21) Appl. No.: **29/195,345**

(22) Filed: **Dec. 9, 2003**

Related U.S. Application Data

(63) Continuation of application No. 29/160,069, filed on May 3, 2002.

(51) **LOC (7) Cl.** **14-03**

(52) **U.S. Cl.** **D14/137; D14/247; D14/217; D14/455**
